(Continued)

Primary Examiner—Cynthia E Ramirez*(74) Attorney, Agent, or Firm*—Brandon N. Sklar, Esq.; Kaye Scholer LLP(57) **CLAIM**

I claim the ornamental design for a pallet, as shown and described.

DESCRIPTION

FIG. 1 is a top perspective view of a pallet in accordance with my design.

FIG. 2 is a right side elevational view thereof.

FIG. 3 is a left side elevational view thereof; and,

FIG. 4 is a rear elevational view thereof. The front elevational view is a mirror image of the rear elevational view of FIG. 4. The bottom view is a mirror image of the top view shown in FIG. 1.
